United States Patent

Des. 238,585
Patented Jan. 27, 1976

238,585

ELECTRONIC TELEPHONE ANSWERING UNIT

James R. Darwood, 12366 E. Charlwood,
Cerritos, Calif. 90701

Filed June 21, 1974, Ser. No. 481,520

Term of patent 14 years

Int. Cl. D14—03

U.S. Cl. D26—14 A

The single figure is a front perspective view of an electronic telephone answering unit showing my new design.

The undisclosed rear, side and bottom is plain and unornamented.

I claim:

The ornamental design for an electronic telephone answering unit, substantially as shown and described.
